ARRANGEMENT FOR SYNCHRONIZING PENDULUM CLOCKS WITH THE AID OF
EXISTING TELEPHONE LINES

Filed June 9, 1923

Inventor:
A. Mayer
By
F. G. Mayer
Attest:

UNITED STATES PATENT OFFICE.

ARMAND MAYER, OF LEVALLOIS-PERRET, FRANCE.

ARRANGEMENT FOR SYNCHRONIZING PENDULUM CLOCKS WITH THE AID OF EXISTING TELEPHONE LINES.

Application filed June 9, 1923. Serial No. 644,357.

To all whom it may concern:

Be it known that I, ARMAND MAYER, a citizen of the French Republic, residing at Levallois-Perret, France, have invented certain new and useful Improvements in Arrangements for Synchronizing Pendulum Clocks with the Aid of Existing Telephone Lines, for which I have filed an application for patent in France on June 14, 1922, and 10 of which the following is a specification.

This invention relates to synchronizing apparatus for pendulum clocks in connection with telephone lines, and the object of the invention is to enable the ordinary 15 telephone lines of central battery telephone systems to be used in the control of synchronous pendulums on the subscriber's premises by means of a master pendulum kept by the exchange.

20 The accompanying drawing shows the synchronizing apparatus applied to a telephone line worked by a central battery 16. The line 1 is permanently connected to one terminal of the central battery 16 and is 25 connected to the return line 2 at the subscriber's end through a condenser 23 and call bell 24, the condenser and call bell being shunted by the telephone 25 when the receiver is lifted, by means of a switch 26 30 as usual.

A soft iron armature 21 is normally held 35 in contact with a contact member 19 by means of a spring 22, so that the circuit of the telephone line 1 is normally closed through the armature 21, contact 19 and the winding of the electro-magnet 17. A second electro-magnet 18 adapted to pull the armature 21 in the opposite direction is supplied 40 with current from a battery 28 through an interrupter 27 which alternately opens and closes the circuit every half second, under the control of a master pendulum 10. When the circuit of the magnet 18 is closed the armature 21 is pulled away from the contact 45 19 and brought into contact with a contact member 20 connected through a resistance 29 to the telephone line 1.

At the receiving station a synchronizing coil 5 associated with a synchronous pendulum in the known manner is connected 50 across the lines 1, 2 in series with the alarm bell 24 and condenser 23, a condenser 9 being connected across the synchronizing

coil in order to facilitate the passage of the call current.

55

The operation is as follows:

When the telephone line is not in use the armature 21 is moved into contact with contact member 20 every time the magnet 18 is excited and thus contacts alternately 60 with the contact members 19, 20. When the armature comes into contact with the member 19 the lines 1 and 2 are connected through the central battery 16 whereby the condenser 23 is charged through the synchronizing coil 5. Thereafter when the armature is moved into contact with the contact member 20, one terminal of the central battery is disconnected from the telephone lines and these are connected together 65 through the resistance 29 so that the condenser 23 is discharged through the coil 5 across the resistance 29. In this way an alternating current of one cycle per second passes through the synchronizing coil 5 thus 70 synchronizing the pendulum associated therewith in the well-known manner.

When the telephone line is in use the circuit of the central battery is closed by the switch 26 and continuous current flows 75 through the line. This current passes through the winding of the magnet 17 and holds the armature 21 in contact with the contact member 19 throughout the time during which the telephone line is in use, the 80 pull of the magnet 18 being insufficient to move the armature against the pull of the magnet 17. A condenser 30 connected between the armature 21 and one end of the winding of the magnet 17 shunts the winding 85 of the magnet 17 and forms a by-pass 90 for the speech currents.

I claim:

A synchronizing apparatus for pendulum clocks in connection with telephone lines 95 with central battery comprising in combination a telephone line, an armature, an armature contact, an electro-magnet at one side of said armature contact, a sub-pendulum, a coil of said sub-pendulum and a condenser in series with said coil, and a central battery in said telephone line sending a synchronizing current into said coil through the intermediary of said magnet armature contact and condenser, a resistance ahead of 100 said condenser, a second armature contact 105

connected therewith, a magnet on the other side of said armature, and a main pendulum sending every half a second a current impulse into said second mentioned magnet for attracting said armature to said second contact so that the said condenser discharges through said resistance, sending into said coil a synchronizing current of opposite di-

rection as the first mentioned synchronizing current, and a condenser in parallel with the magnet on the battery side designed to prevent the access of the telephone currents to said battery magnet. 10

In testimony whereof I affix my signature.

ARMAND MAYER.
